UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

SHUTTER.

Application filed May 3, 1920. Serial No. 378,376.

To all whom it may concern:

Be it known that I, RUDOLPH HOFFMAN, a citizen of the United States, residing at Kankakee, in the county of Kankakee and State of Illinois, have invented certain new and useful Improvements in Shutters, of which the following is a specification.

The invention relates in general, to shutters and more particularly contemplates the provision of a flexible shutter adapted to close an opening in the front wall of a kitchen cabinet or the like.

The object of the invention is to provide a shutter of advantageous construction which may be manufactured at a relatively low cost and is easily operable from a closed position over the opening into an inoperative position at one edge of the opening.

A further object of the invention is to provide a shutter which comprises a plurality of leaves connected together in an improved manner enabling the leaves to swing relative to each other from an extended relation to a collapsed relation and vice versa, with a smooth and easy action.

The objects of the invention thus generally stated, together with other advantages which will be apparent from the following description, may be attained by the construction and arrangement illustrated in the accompanying drawings wherein I have shown a preferred embodiment of the invention. It is to be understood, however, that although the invention is hereinafter described with considerable particularity, it is not intended that it shall be limited thereby in the interpretation of the appended claims, except as may be necessitated by the state of the prior art.

In the drawings, Figure 1 is a perspective view of a kitchen cabinet having a shutter constructed in accordance with my invention. Fig. 2 is a fragmentary vertical sectional view transversely of the shutter and the upper portion of the cabinet. Fig. 3 is a fragmentary horizontal section through the upper portion of the cabinet, showing the uppermost leaf swung into its horizontal or inoperative position. Fig. 4 is a fragmentary sectional view transversely of the upper portion of the cabinet and showing the leaves collapsed into their inoperative position. Fig. 5 is a fragmentary vertical sectional view longitudinally of the upper portion of the cabinet showing the leaves in

their collapsed relation. Fig. 6 is a fragmentary rear view of the leaves in the position shown in Fig. 4.

The cabinet to which the shutter is shown as applied may be of any preferred form and herein comprises a lower or base portion 7 having a top wall forming a work table 8, and an upper or top section 9 having an opening 10 therein adapted to be closed by a shutter designated generally by 11.

The shutter comprises a plurality of leaves 12 operatively connected together by means of a plurality of hinge members 13. One end of the shutter, as, for example, the upper end, is pivotally supported in the cabinet upon a rod 14, and the lower end of the shutter carries a rod 15 providing guide studs at its opposite ends operatively engaging in guideways 17 provided upon the opposite side walls of the compartment of the cabinet which is closed by the shutter.

The leaves 12 are formed at opposite ends with side portions 18 which, when the leaves are in their extended relation, project in a rearward direction. Substantially centrally of said side portions are pivotally secured the hinge members 13 as at 19. Said members 13 are in the form of flat bars or links, and the pivots 19 are also located centrally of the hinge members.

The links 13 for the intermediate leaves are pivotally connected at their opposite ends with the adjoining edges of the adjacent leaves. Thus the upper ends of the links are connected to the lower edges of the upper adjacent leaves by means of pivots 20 entered through the lower ends of the side portions 18 of the leaves; and the lower ends of the members are connected to the upper edges of the lower adjacent leaves by means of pivots 21 entered through the upper ends of the side portions 18 of the leaves. In the case of the links of the uppermost leaf, their upper ends are pivotally mounted upon the rod 14 mounted in the cabinet. As shown in Fig. 3 said rod may be mounted in the opposite walls of the compartment which is closed by the shutter, as, for example, by being supported at the upper ends of the guideways 17. Said guideways may be of any suitable construction being herein formed from sheet metal members 23 secured to the side walls of the compartment and bent to provide the guide-

way 17. The lowermost leaf of the shutter carries at its lower edge in the side portions 18 thereof, the guide rod 15 for engaging in the guideway 17. In this instance the 5 hinged members connecting the lowermost leaf to the upper adjacent leaf are shorter than the other links, being terminated below the pivots 19, as shown in Fig. 2.

It will be seen that the members 13 and 10 the side portions 18 of the leaves together form in effect a lazy-tong construction, as shown clearly in Figs. 2 and 4, which permits of the relative swinging movement of the leaves from operative position across 15 the opening 10 in the cabinet into collapsed relation at one edge of the opening. To permit of the free and substantially unrestricted pivotal movement of the leaves with respect to each other, the lower or rear edges 20 of the side portions 18 of the leaves are bent outwardly, as shown in Figs. 2 and 6 to provide flat offset portions 22 upon which the links 13 may bear. This peculiar shaping of the side portions 18 also permits of 25 the nesting of the leaves, the offset portions 22 of one leaf being adapted to overlie the side portions of the adjacent leaf.

At their upper edges the leaves are preferably bent inwardly, as shown at 12^a (Fig. 30 2), to underlap the lower edges of the upper adjacent leaves. To permit of such interfitting relation of the leaves, the opposite ends of the inwardly bent portions are notched, as shown at 12^b (Fig. 3), so as to 35 receive the lower ends of the side portions 18 (Fig. 2).

To facilitate the operation of the shutter from its operative position closing the opening to its inoperative position, the lowermost leaf may be provided with suitable finger pieces or hooks 24 which are shaped 40 so as not to interfere with the folding of the leaves into a compact stack. To support the leaves when moved into their inoperative position, a suitable spring catch member 45 25 is provided which may be secured at the upper edge of the opening 10 of the cabinet.

It will be seen that I have provided a shutter which is of a very simple construction and which is adapted to provide a very efficient closure for the cabinet opening. The leaves are operatively associated in such a manner as to be capable of being moved from an extended relation to an inoperative 50 or collapsed relation with the expenditure of a minimum amount of effort on the part of the operator, and the operation of the parts is smooth and may be accomplished with substantially no noise.

60 I claim as my invention:

1. A shutter for kitchen cabinets and the like comprising, in combination with a frame defining an opening to be closed, a plurality of leaves, guideways within the cabinet at the opposite edges of the opening, and means

and means operatively connecting the leaves together whereby to permit of their movement from an extended edge to edge relation into a collapsed relation at one edge of the opening and vice versa, said connecting 70 means comprising a lazy tong linkage at each edge of the shutter, and each of said linkages including an upwardly and forwardly extending bar pivoted substantially centrally of the uppermost leaf and having 75 its free end pivotally supported at the upper ends of said guideways, and guide studs operable in said guideways, said studs being located near the lower forward edge of the lowermost leaf; the arrangement being such 80 that the leaves when extended substantially abut the rear face of said frame and when collapsed extend rearwardly into the cabinet with the connecting means concealed at all times by the frame. 85

2. A shutter for kitchen cabinets and the like comprising a plurality of leaves made of sheet metal and having at their opposite ends flanges projecting substantially at right angles thereto, means operatively connecting 90 said leaves together comprising a bar pivoted to each of the flanges of said leaves on an axis disposed substantially midway between the upper and lower edges of the leaf, said bars and flanges being pivotally connected together to form a lazy tong linkage at each edge of the shutter, a pair of guideways within the cabinet and located immediately rearward of the plane of the opening to be closed and parallel thereto, a 95 rod mounted at the upper ends of said guideways and extending transversely of the opening, the bars pivoted to the opposite ends of the uppermost leaf of the shutter being pivotally mounted at their upper forward ends 100 on said rod, and a rod carried by the lowermost leaf near the lower forward edge thereof and having its opposite ends engaging in said guideways whereby the leaves are maintained bodily at all times rearwardly 105 of the plane of the opening.

3. A shutter for kitchen cabinets and the like comprising, in combination with a frame defining an opening to be closed, a plurality of leaves, guideways within the cabinet at 110 the opposite edges of the opening, and means operatively connecting the leaves together whereby to permit of their movement from an extended edge to edge relation into a collapsed relation at one edge of the opening and vice versa, said connecting means comprising a lazy tong linkage at each edge of the shutter, and each of said linkages including an upwardly and forwardly extending bar pivoted substantially centrally of the uppermost leaf and having its free end pivotally supported at the upper ends of 115 said guideways, guide studs operable in said guideways, said studs being located near the lower forward edge of the lowermost leaf; 120

the arrangement being such that the leaves to engage with one of the leaves when the when extended substantially abut the rear latter are in their collapsed relation whereby face of said frame and when collapsed extend rearwardly into the cabinet with the to maintain the shutter in position at the 10 connecting means concealed at all times by upper edge of the opening. In testimony whereof, I have hereunto set the frame, and a device secured to the upper my hand.

edge of the opening and adapted yieldably

RUDOLPH HOFFMAN.
